UNITED STATES PATENT OFFICE.

ABBIE W. HOLMES, OF PROVIDENCE, RHODE ISLAND.

DESIGN FOR AN IDENTIFICATION TAG.

Application filed May 9, 1924. Serial No. 9,531. Term of patent 3½ years.

To all whom it may concern:

Be it known that I, ABBIE W. HOLMES, a citizen of the United States, residing at Providence, in the county of Providence and State of Rhode Island, have invented a certain new, original, and ornamental Design for an Identification Tag, of which the following is a specification.

In the accompanying drawings which form a part of this specification—

Figures 1 and 2 are a front view and a side view respectively of an identification tag showing my new design.

I claim:

The ornamental design for an identification tag, as shown.

ABBIE W. HOLMES.
